United States Patent Office

Des. 228,031
Patented July 31, 1973

228,031

BOAT

Marcel Jean Tabur, Le Mans, France, assignor to
G.M.T., S.A., Le Mans, France

Filed Feb. 1, 1971, Ser. No. 111,782

Term of patent 14 years

Int. Cl. D12—06

U.S. Cl. D71—1 Q

FIG. 1 is a front elevation view of a boat showing my new design;

FIG. 2 is a side elevation view of the boat of my new design;

FIG. 3 is a top view of the boat of my new design;

FIG. 4 is a view similar to FIG. 2 but from the opposite side thereof;

FIG. 5 is a rear elevational view of the boat of my new design; and

FIG. 6 is a bottom view of the boat of my new design. I claim:

The ornamental design for a boat, as shown.
